UNITED STATES PATENT OFFICE.

ARTHUR E. BROUGHTON, OF MINNEAPOLIS, MINNESOTA.

APPARATUS FOR REMOVING AIR FROM STEAM-CONDENSING SYSTEMS.

Application filed July 10, 1924. Serial No. 725,316.

As is well known, the presence of air in steam condensing systems interferes with the proper distribution of heat and lowers the efficiency generally, but it is frequently impossible to eliminate air altogether from such systems. Attempts continuously and economically to remove the air have been unsuccessful, as far as applicant is aware, either because the apparatus provided is too expensive, or because the amount of power required to withdraw the air is excessive.

It is my object to provide a novel and simple method and apparatus for continuously withdrawing air from a steam condensing system with a minimum expenditure of power.

While the present invention may be applied to almost any steam heating, drying or condensing system, I find that one such system to which it is particularly applicable is the dryer of a paper making machine, such as that described in my co-pending application for patent on heating system for paper dryers, filed March 15th, 1924, Serial No. 699,464.

To secure best results with the apparatus of said co-pending application, it is necessary to place certain of the traps and receivers at a lower level than the dryers and this is impractical where there is no space provided by a basement or other room, beneath the paper machine. Where there is no such space, the header or headers for condensate, connected to the several dryers by individual pipes, are located upon the floor or just above the floor level and it is essential that what ever apparatus is provided to remove air from the system should be positioned above floor level and be adapted to withdraw air upward from the headers. In a system of this kind steam, as well as condensate, is present in the headers and I have discovered that air collects in the headers upon the surface of the condensate.

In the accompanying drawings I have illustrated diagrammatically apparatus suitable for removing air from a header of the kind described above. Referring to the drawings, Figure 1 is a side elevation of the apparatus, and Fig. 2 is a transverse section of the header and condensate outlet, showing the air withdrawal pipe.

In the drawings the numeral 3 indicates the condensate header which is in direct communication with the interior of the dryers, being connected therewith by a series

of pipes 4. These pipes 4 allow steam as well as condensate to flow from the dryers to the header 3. Outlet pipes 5, communicating with the header 3 somewhat above the bottom thereof, are adapted to carry off the condensate and to maintain a substantially constant level of water in the header 3.

To remove the air, which collects upon the surface of the water in the header, I place withdrawal pipes 6 at suitable intervals (preferably from 5 to 8 feet apart) along the header and extend said pipes into the header so that the open ends are just above the water level. As shown in Fig. 2, this can be conveniently done by forming a long thread on each of the pipes 6 and turning them into suitable bushings 7 placed in the upper periphery of the header. The several air pipes 6 are joined to a common cross pipe 8 which, in turn, is connected by a pipe 9 with a closed receiver 10. Mounted in communication with the receiver 10 is a thermostatic valve 11 of common type adapted to allow air to escape readily from said receiver, but arranged to close when steam at or near the temperature of that in the header 3 starts to escape through the valve.

The operation of my invention is as follows. When the header 3, above the level of condensate therein, is filled with steam and before a substantial amount of air has collected in said header, the pipes 6, 8 and 9 and the receiver 10 will also be filled with steam so that the valve 11 is closed. However as air collects upon the surface of the condensate it will be drawn into the receiver 10 by the reduced pressure caused by gradual condensation which takes place in the receiver and connecting pipes. Air will thus pass into the receiver 10 until the temperature therein has been reduced sufficiently to cause the valve 11 to open. The air will now be expelled through the valve 11 by steam pressure in the header which remains practically constant. When the air has been replaced by steam the valve 11 again closes and the above described operation is repeated.

As will be readily understood, the valve 11 operates only at substantial intervals when a comparatively large amount of air has collected in the receiver 10. Thus the wear on the valve 11 is reduced to a minimum and there are no other parts of the apparatus which can become worn or get

out of order. The operation of withdrawing air from the header 3 is continuous and automatic and the loss of steam in condensation in the receiver 10 and connecting pipes is slight. On the other hand the application of my invention to a paper making machine greatly increases the speed at which the dryers can be operated and generally improves efficiency.

10 Having described my invention, what I claim as new and desire to protect by Letters Patent is:

1. In mechanism for removing air from steam condensing systems, the combination 15 with a receptacle adapted to be supplied with steam, of means for permitting withdrawal of air from said receptacle substantially continuously, a receiver adapted to collect the air so removed and means for 20 periodically allowing the escape of air from said receiver.

2. In mechanism for removing air from steam condensing systems, the combination 25 with a receptacle for condensate adapted to be supplied with steam, of means for permitting withdrawal of air and steam from near the surface of said condensate, a receiver adapted to collect the air and steam so removed and means for permitting the 30 escape of air from said receiver.

3. The combination with a long and relatively narrow receptacle for condensate disposed substantially horizontally, of a series 35 of spaced pipes communicating at one end with said receptacle, a common receiver for air connected to the opposite ends of the several pipes and means on said receiver adapted to allow the escape of air therefrom.

4. The combination with a condensate receptacle having a continuous supply of 40 steam, of a pipe projecting into said receptacle and having an opening adjacent to the surface of the condensate therein, a receiver in communication with said pipe adapted to permit accumulation of air, said receiver being positioned above said receptacle and arranged to drain thereinto, and a thermostatic valve connected to said receiver and adapted to allow the escape of cooled air therefrom but preventing the escape of 45 steam.

5. The combination with a substantially horizontal header for condensate adapted to be supplied with steam, of a series of spaced pipes communicating with said header, a 55 common receiver for the several pipes arranged to drain into said header, and a thermostatic valve connected to the receiver and arranged to allow the escape of cooled air therefrom but preventing the escape of 60 steam.

6. In mechanism for removing air from a steam condensing unit, the combination with a condensate receptacle connected by 65 pipes with said unit, of a series of air withdrawal pipes communicating with said receptacle and extending upward therefrom, a common receiver for the several air withdrawal pipes connected to the upper ends of 70 said pipes and of a size adapted to allow accumulation of a substantial volume of air therein and a valve on said receiver arranged to allow the escape of air therefrom.

In testimony whereof, I have hereunto signed my name to this specification:

ARTHUR E. BROUGHTON.
